(57) **CLAIM**

The ornamental design for a bicycle rack slot as shown and described.

DESCRIPTION

FIG. 1 is a perspective view of a bicycle rack slot showing the claimed design;

FIG. 2 is another perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is another perspective view of the bicycle rack slot, shown in an open state; and,

FIG. 10 is another perspective view of the bicycle rack slot, shown in use, mounted on a bicycle rack.

The broken lines of the bicycle rack shown in FIG. 10, illustrates environment and form no part of the claimed design.
